[57] CLAIM

The ornamental design for a basketball return for attachment to basketball hoops, as shown and described.

DESCRIPTION

FIG. 1 is an exploded front elevation view of a basketball return for attachment to basketball hoops, embodying my new design;

FIG. 2 is a top plan view thereof;

FIG. 3 is a front elevation view thereof;

FIG. 4 is a side elevation view thereof, viewed from the left of FIG. 3, the opposite side elevation being substantially the mirror image thereof;

FIG. 5 is a rear elevation view thereof; and

FIG. 6 is a bottom view thereof.
